UNITED STATES PATENT OFFICE

133,342

DESIGN FOR A TEXTILE FABRIC

Max Sokoloff, Cedarhurst, N. Y.

Application July 4, 1942, Serial No. 107,416

Term of patent 3½ years

To all whom it may concern:

Be it known that I, Max Sokoloff, a citizen of the United States, residing in Cedarhurst, in the county of Nassau and State of New York, have invented a new, original, and ornamental Design for a Textile Fabric, of which the following is a specification, reference being had to the accompanying drawing, forming part thereof.

The figure is a plan view of a textile fabric showing my new design.

The fabric is shown on a dark background in order to bring out more clearly the details of the design.

I claim:

The ornamental design for a textile fabric, substantially as shown and described.

MAX SOKOLOFF.
